UNITED STATES PATENT OFFICE.

ARTHUR G. WILLARD, OF LOS ANGELES, AND CHARLES E. WILCOX, OF BAKERSFIELD, CALIFORNIA; SAID WILCOX ASSIGNOR TO WILLIAM W. WILSON, OF LOS ANGELES, CALIFORNIA.

WELL-BORING APPARATUS.

1,149,486.

Specification of Letters Patent. Patented Aug. 10, 1915.

Application filed April 28, 1911. Serial No. 623,808.

To all whom it may concern:

Be it known that we, ARTHUR GAY WILLARD and CHARLES E. WILCOX, citizens of the United States, residing, respectively, at Los Angeles, in the county of Los Angeles and State of California, and at Bakersfield, in the county of Kern and State of California, have jointly invented new and useful Improvements in Well-Boring Apparatus, of 10 which the following is a specification.

This invention relates to the art of well boring or well drilling, and more particularly to well borers which, in standard practice, are provided with rotary tops where- 15 by are caused the rotation of the boring tool and the string of pipe sections extending upwardly from the same to the rig, whereby the same is raised and lowered in carrying on the drilling operation.

20 Numerous means have been devised for causing the actuation of the boring tool and the pipe-section string in the rotation of the rotary top. These means have in various ways provided for the connection and dis- 25 connection of the string of pipe sections from the rotary top, so that the string might be raised or lowered, and made fast to the rotary top, in the drilling operation. Usually, the latter means prevent raising or 30 lowering of the string and the boring tool when the rotary top and the string are in operative connection so that rotation of the top is transmitted to the string and the tool.

According to the present invention, we 35 provide means for operatively connecting the rotary top and the string of pipe sections carrying the boring tool, such means permitting of variation of degree of positiveness of such operative connection, so 40 that under undue or extreme stress brought to bear upon the string and tool, such operative connections will yield in their holding action and permit relative rotary movement between the top and the string and boring 45 tool.

We also provide means between the string of pipe sections and the operative connections, for so holding and guiding the string that the string and the boring tool are free 50 to play vertically although locked against

rotation relative to the rotation of the rotary top, as long as the aforesaid means of operative connection whereby rotary movement is imparted to the string are positively acting. The provision of such means for 55 holding the string and permitting its vertical movement at all times results in great convenience in conducting the boring operation, as the string and boring tool may be raised or lowered at any point in the boring 60 operation without operatively disconnecting the string and tool from the top.

The invention has for its object to provide improvements of the general nature above stated which will be superior in point 65 of relative simplicity and inexpensiveness of construction, facility in control and operation, positiveness in operation, and freedom from liability to disorder or impairment of its parts and working efficiency, 70 and which will be generally superior in serviceability and adaptability to varying conditions of use and service.

With the above and other objects in view, and with the above general features of construction and organization entering into the practice of the invention, the invention consists in the novel provision, construction, formation, organization, combination and relative arrangement of parts, members and 75 features, all as hereinafter described, shown in the drawings and finally pointed out in claims.

In the drawings: Figure 1 is a top plan view, partly in section and partly broken 80 away for clearness of illustration, of a rotary top for well borers organized in accordance with the invention; Fig. 2 is a vertical sectional view of the same, partially 85 in full lines, taken upon the line 2—2, Fig. 1, and also of the base upon which the same is mounted for rotation; Fig. 3 is a fragmentary side elevation of pipe sections modified and organized in accordance with the invention for use in connection with the 90 improved rotary top; Fig. 4 is a transverse sectional view taken through one of the pipe sections shown in Fig. 3, upon the line 4—4, Fig. 3, the showing therein being 95 given a quarter turn from the position 100

shown in Fig. 3; Fig. 5 is an enlarged fragmentary view of one of the pipe sections shown in Fig. 3, viewed in the same line of vision as the showing in Fig. 4; and 5 Figs. 6 and 7 are vertical sectional views of members of means shown in Figs. 1 and 2 for holding and guiding the pipe sections, and to which the operative connections between the pipe sections and the rotary top 10 are applied in service.

Corresponding parts in all the figures are denoted by the same reference characters.

Referring with particularity to the drawings, A designates a rotary table organized in accordance with present practice, or in any preferred manner, and mounted upon rollers α , for rotation, B designating means for imparting rotation to the table which latter is provided with a rotary table top 20 C organized in accordance with the present invention.

D designates pipe sections modified and constructed to be used in carrying out the invention.

25 E designates operative connections whereby rotary motion of the table A is imparted to the pipe sections D and the boring tool carried at the lower end thereof.

30 F designates means disposed between the pipe sections and the operative connections E, such means serving to hold the pipe sections against rotary movement relative to the rotary movement of the rotary table A when the operative connections E are acting 35 to rotate the pipe sections; said means F permitting vertical movement of the pipe sections.

The present invention is not concerned in the manner of or means for mounting the 40 table A or of imparting rotary motion thereto, but only with the rotary top C comprising the operative connections E, the means F, and the particularly organized and modified pipe section or sections D which 45 act with the means F.

In carrying the invention into practice, in one form of organization and embodiment of the same, we provide the usual rotary table A in the form of an annulus, through 50 the central opening of which the pipe sections and boring tool are lowered and raised, and within which central opening the means E and F are installed. The means F comprise two sleeves, 8 and 9 respectively, the 55 sleeve 9 being provided adjacent to its top with a plurality of spaced recesses 10 within which fit heads or lugs 11 projecting outwardly from the periphery of the sleeve 8, constituting interlocking means between 60 said sleeves. The sleeve 9 is provided at its lower portion with a reduced portion 9^a forming an annular shoulder 9^b which fits and rests upon an annular shoulder 9^c formed upon the table A. The sleeve 8 is

provided with vertical spaced and preferably diametrically opposed recesses or grooves 12 which receive lateral ribs or bars 13 upon the upper pipe section or sections, in such relation that such pipe section or sections may have vertical play within the 65 sleeve 8, at the same time being prevented from rotation within such sleeve 8. The upper section or sections D of the string of pipe sections are provided with the ribs or bars 13, preferably diametrically opposed, 70 and such bars 13 may be held in place by curved or approximately semi-circular clamps 14 secured to such pipe section or sections exteriorly, as by countersunk screws 15 or the like; the ends of the clamps 14 are formed into outwardly projecting flanges 16 between which the bars 13 extending longitudinally of the pipe section are firmly held, as by rivets 17. Preferably two of the pipe 75 sections of standard length are employed, as shown in Fig. 3, the same being connected by a union or joint 18, so that a total length 80 of the composite or double section at the top of the string of sections will be provided to cause operative engagement of such section with the sleeve 8 during the lowering of the string a distance fully equivalent to or more 85 than equal to the length of one section of the string. The composite section D as above 90 organized is always retained at the upper end of the string, fresh sections being supplied directly beneath it as the boring operation proceeds. d designates in each instance the pipe section proper, and 19 designates a joint or union whereby the sections 95 beneath the top composite section D are connected with the latter.

The means E, as shown, for operatively connecting the pipe section D with the rotary table A, through the agencies of the 100 sleeves 8 and 9, comprises a band or strap 20 passed around the smooth outer periphery of the sleeve 9, in a suitable annular chamber 21 formed in the table A, said band or 105 strap being provided at one end with a knuckle 22 which receives a pin 23 seated vertically in the table A and holding the respective end firmly in position; the band or strap 20 being bifurcated at the same end as shown in Fig. 2, to receive the other end 110 of said band or strap which passes through a head 24 formed in the table A between the chamber 21 and a communicating chamber 25 formed in the table; said latter end of the strap or band 20 being screw threaded, as at 26, and there being a nut 27 applied thereto in position to bear upon the head 24. The chamber 25 opens outwardly through the top of the table so that a suitable implement may be applied to the nut 27 to turn 115 the same and cause the band or strap 20 to be tightened or loosened in its grip upon the sleeve 9.

The pipe sections D, or the sections proper, d, may be of any preferred cross-sectional formation.

The operation, method of use and advantages in the improvements in rotary tops for well borers constituting the invention will be readily understood from the foregoing description, taken in connection with the accompanying drawings and the following statement:—The string of pipe sections including the composite section D is free to play vertically within the sleeve 8, the bars 13, which may be applied to the sections D in any preferred manner, loosely fitting the grooves 12. But said ribs or bars cause the interlocking of the pipe sections and the sleeve 8 against relative rotation of the same; and the sleeve 8 and the sleeve 9 are locked against relative rotation by the interlocking heads 11 and recesses 10. When the nut 27 is screwed toward the head 24 in the table A, the band or strap 20 is tightened upon the sleeve 9, locking said sleeve, and the sleeve 8 which is interlocked therewith, and the pipe sections D which are interlocked with the sleeve 8, in such union or inter-relation that rotation of the table A is imparted to the section or sections D and the string and boring tool beneath the same. The said sections and tool are free to move vertically, so that they may be raised or lowered without rotatably disconnecting the same from the table, and so that they will yield vertically under undue stress upon or resistance to the tool. Furthermore, the frictional engagement of the band or strap 20 upon the sleeve 9 may be predetermined to the end that the sleeves 8 and 9 and the pipe sections and boring tool will be automatically permitted to slip within the grip of the means E including the strap or band 20, terminating rotation of the string and tool, during the rotation of the table A, in case a particular degree of undue stress or resistance is brought to bear upon the string and the tool, as by some excessively hard formation or obstruction encountered in the boring operation. The vertical play permitted the string and the tool, and the permitted slipping of the string and tool within the grip of the rotating table, both of which are permitted by the provision of the means, and in the manner, as above described, obviates breakage and other objectionable destruction or disruption or derangement of working parts; and the string and tool may at all times be raised or lowered, or may rise and fall, as required in the drilling operation without destroying the rotative relation between the string and the table.

The drilling string is operatively connected with the rotation imparting means between the top and bottom of the rotary

table, so that the string may play vertically 65 or longitudinally, which assures a positive transmission of power to the string and permits of strong construction; and the sleeve or bushing which co-operates with the string and the table, or the plurality of 70 such parts if preferred, are in the main accommodated and held in position by the table and between the top and bottom thereof in the central opening therein.

We do not desire to be understood as limiting ourselves to the particular provision, construction, combination, association and relative arrangement of parts, members and features herein shown and described; but reserve the right to vary the same, in adapting 80 the improvements to varying conditions of use, without departing from the spirit of the invention and the terms of the following claims.

Having thus described our invention we 85 claim and desire to secure by Letters Patent:—

1. In improvements of the character disclosed, a rotary table; and means for connecting the table with a boring device in rotative couple; said means being adjustable 90 with respect to variable strain acting to interrupt such rotative couple during rotation of the table.

2. In improvements of the character disclosed, a rotary table; and means for connecting the table with a boring device in rotative couple; said means being adjustable with respect to variable strain acting to interrupt such rotative couple during rotation 100 of the table, and permitting vertical movement of such boring device with respect to the table when in rotative couple therewith.

3. Improvements of the character disclosed, comprising a rotary table, a member formed for rotative connection with a boring device, said member permitting vertical movement of such boring device, and adjustable means for yieldingly connecting said 105 member with the rotary table for rotation therewith whereby said rotative connection may be interrupted during rotation of the table and under prescribed strain.

4. Improvements of the character disclosed, comprising a rotary table, a sleeve, means for rotatively connecting a boring device with said sleeve, and adjustable means for yieldingly connecting said sleeve with the rotary table for rotation therewith 110 whereby the rotative connection of the sleeve and the rotary table may be interrupted during rotation of the table and under prescribed strain.

5. Improvements of the character de- 125 scribed, comprising a rotary table, a sleeve, means for rotatively connecting a boring string with said sleeve, and means for yield-

ingly connecting said sleeve with the rotary table for rotation therewith, said last named means comprising a strap or band applied to said sleeve and fixed to said table at one end and provided at the other end with means for varying the frictional engagement thereof with said sleeve.

In testimony whereof, we have signed our

names to this specification in the presence of two subscribing witnesses.
